UNITED STATES PATENT OFFICE.

JOSEPH E. CONDON, OF CLINTON, IOWA, ASSIGNOR TO PETER H. KELLY, OF CLINTON, IOWA.

CLOTHES-WRINGER.

1,113,603.

Specification of Letters Patent. Patented Oct. 13, 1914.

Application filed June 2, 1913. Serial No. 771,262.

To all whom it may concern:

Be it known that I, JOSEPH E. CONDON, a citizen of the United States, residing at Clinton, in the county of Clinton and State of Iowa, have invented a new and useful Improvement in Clothes-Wringers, of which the following is a specification.

My invention relates, particularly, to an improvement in means for effecting quickly 10 the release of the movable clamping roll from the companion roll in a clothes-wringer or mangle, in the event of accident, such as the hand of the operator or laundry work becoming caught between the rolls.

15 In the accompanying drawings—Figure 1 is a view in front elevation of a clothes-wringer equipped with my invention. Fig. 2 is a plan view of the same. Fig. 3 is an end view of the same. Fig. 4 is a broken 20 view similar to Fig. 1, partly sectional to disclose interior details. Fig. 5 is an enlarged section taken at the line 5 on Fig. 4 and viewed in the direction of the arrow; and Fig. 6, a perspective view of one of 25 the two similar wedge devices employed.

The general construction of the wringer illustrated for showing my invention is one in common use: Upright-side stiles 7 contain slots 8, one being shown in Fig. 3; 30 extending from the upper ends of the stiles and provided in their lower ends with bearings for the drive-shaft 9 of the lower roll 10. The upper roll 11 and lower roll are journaled to work in metal heads 12, at the 35 inner sides of the side stiles, the upper roll being vertically movable in its bearings relative to the roll 10 for the coöperation of the rolls in feeding the work between them, the pressure against the roll 11 being 40 exerted at its journal-ends through the medium of adequately stiff spiral springs 13, each confined between a bearing 14 straddling a journal and a tongue 15 projecting over the top of the respective springs from 45 the adjacent end of a cross-bar 16, the tongues 15 resting upon the opposite springs 13.

Extending at its opposite ends through the slots 8 in the stiles 7, and movable up 50 and down therein, is a pressure-bar 17 provided at its opposite ends with set-screws 18, which pass loosely through yokes 19 surmounting the stiles 7, and have threaded engagement with the ends of the bar 17, 55 the lower ends of the set-screws 18 being

adapted to coöperate with the tongues 15 for placing the desired compression tension on the springs 13.

The positioning of the pressure-bar 17 for placing the springs 13 under compression and the release of the pressure-bar to release the movable clamping roll from the companion roll, is effected by the following described means: Swingingly mounted in the slots 8, on pins 20, secured in the upper 60 ends of the stiles 7, are links 21 connected together at their lower ends by pins 22 carrying rollers 23, the links 21 being located intermediate the set-screws 18 (Fig. 4) and connected together through means 65 of a toggle formed of the levers 24 and 24^a pivotally connected at their adjacent ends, as indicated at 25, and at their opposite ends to the pins 22, the lever 24^a being somewhat longer than the lever 24 and being 70 provided with a handle 26, the parts just described being preferably so positioned that when the links 21 are swung to the position illustrated in Fig. 4, the pivot 25 will extend below the plane occupied by the pivots 22. The upper surface of the pressure-bar 17 is provided, 75 toward its opposite ends, but preferably intermediate the set-screws 18, with inclined surfaces 27, which incline downwardly 80 toward the center of the bar 17 (Fig. 4) and terminate at their upper ends in shoulders 28, these inclined surfaces being preferably provided on metal plates 29 secured in any desirable manner to the bar 17. 85

It will be understood from the foregoing description that when the toggle formed of the levers 24 and 24^a is swung to the position illustrated in Fig. 4, the rollers 23 will ride upon the inclined surfaces 27, thus 90 forcing the pressure-bar 17 downward and with it said set-screws 18, which latter in bearing at their lower ends against the tongues 15 place the springs 13 under compression and consequently force the roll 11 95 against the roll 10, the degree of pressure exerted upon the springs 13 depending upon the adjustment of the said set-screws 18 in the pressure-bar 17. Should, for any reason, it be desired that the upper roll 100 11 be released, the operator, by striking the handle 26 an upward blow, breaks the toggle, thus swinging the links 21 and roller 23 toward each other from the position illustrated in Fig. 4 and by removing said 110

rollers from the cam-surfaces 27 the springs 13 are free to expand and thus the pressure is taken off of the roll 11.

I realize that considerable variation is possible in the details of construction of my present improvement thus specifically shown and described, and I do not intend by illustrating a single, specific, or preferred form to limit my invention thereto; my intention being in the following claims to claim protection upon all the novelty there may be in the device as broadly as the state of the art will permit.

What I claim as new and desire to secure 15 by Letters Patent is—

1. In a clothes-wringer, the combination with the adjustable roll of the device, and springs confined against its ends, of means provided with inclined surfaces and operating, when depressed, to place said springs under tension, members pivotally supported on the frame of the device to swing in a substantially vertical plane and adapted when swung to one position to engage said cam-surfaces and depress said first-named means, and means for releasing said members.

2. In a clothes-wringer, the combination with the adjustable roll of the device, and springs confined against its ends, of means provided with cam surfaces and operating, when depressed, to place said springs under tension, members pivotally supported on the frame of the device to swing in a substantially vertical plane and adapted when swung to one position to engage said cam-surfaces and depress said first-named means, and means connected with said members for releasing the latter.

3. In a clothes-wringer, the combination with the adjustable roll of the device, and springs confined against its ends, of means provided with inclined surfaces and operating, when depressed, to place said springs under tension, members pivotally supported on the frame of the device and releasably engaging said inclined surfaces, and a toggle

connected with said members, for the purpose set forth.

4. In a clothes-wringer, the combination with the adjustable roll of the device and 50 springs confined against its ends, of a pressure-bar having inclined surfaces thereon, set-screws adjustable therein for coöperation with the upper ends of the springs, members pivoted on the frame of the device for coöperation with said inclined surfaces, and a toggle connecting said members together, for the purpose set forth.

5. In a clothes-wringer, the combination with the adjustable roll of the device, and 60 springs confined against its ends, of a pressure-bar, members pivotally supported on the frame of the device to swing in a vertical plane and adapted when swung to one position to engage said pressure-bar and depress 65 it, and means connecting said members together for simultaneous operation.

6. In a clothes-wringer, the combination with the adjustable roll of the device, and 70 springs confined against its ends, of a pressure-bar, members pivotally supported on the frame of the device to swing in a vertical plane and adapted when swung to one position to engage said pressure-bar and depress 75 the latter, and toggle mechanism connected with said members for the purpose set forth.

7. In a clothes-wringer, the combination with the adjustable roll of the device, and 80 springs confined against its ends, of a pressure-bar, members pivotally supported on the frame of the device adjacent to opposite ends of said pressure-bar to swing in a vertical plane and adapted when swung to one position to depress said bar, and means connecting said members together for simultaneous operation.

JOSEPH E. CONDON.
